HOSTIERY DRYING FORM

Application filed January 21, 1930. Serial No. 422,422.

This invention relates to hosiery drying forms and particularly to the provision in such forms of means for reinforcing them against internal and external pressure.

It is an object of the invention to provide a hosiery drying form with reinforcing means located within the interior of the form and which functions to prevent separation of the side members of the form due to the pressure of the heating medium within the form.

A further object is to provide a hosiery drying form with reinforcing members secured to the sides of the form and having portions which are interengaged or interlocked.

A further object of the invention is to provide a hosiery drying form with reinforcing means located within the form substantially along its longitudinal center whereby to increase the resistance to torsional strain and thus to prevent separation of the sides of the form at their joint.

The present invention finds its utility principally in connection with hosiery drying forms made of sheet metal, such as sheet steel, the form being constructed of two sheets cut to shape and welded or otherwise suitably secured together along their edges. It has been found in practice, particularly with so-called "outsize" forms, that the forms are apt to swell due to the pressure of the heating medium within the form and there is thus a tendency for the sides to pull apart at their joint. To prevent this, it has been proposed to construct the form of very heavy gauge metal which will remain rigid and which will be able to withstand internal pressures but so to construct the form is expensive and does not offer a certain remedy for this condition. Furthermore, when the form is constructed of very heavy gauge metal considerable grinding must be done in order to reduce the edges to the necessary degree of sharpness for creasing the hosiery boarded on the form.

It has also been found that forms constructed of sheet metal are apt to be dented during their construction as for example in the finishing process when the exterior surface of the form is subjected to treatment for producing thereon a roughened surface or in other operations in which the form is subjected to external pressure.

By the use of our invention, the foregoing disadvantages and defects of prior constructions are successfully overcome. A reinforced form according to our invention may be made of much lighter metal than has heretofore been employed and yet it will successfully withstand external pressure during the construction of the form as well as internal pressure of the heating medium during the operation of the form. Stainless sheet steel is frequently used in the construction of forms by reason of its ability to resist rust and corrosion. Since such material is relatively expensive it is desirable to use stock of light gauge so that the cost of production of forms of this character may be in proportion to those made of less expensive materials. In accomplishing such purpose the present invention is of great value since it overcomes any weakness in the forms which may arise from the use of light stocks in the construction thereof, its importance increasing the lighter the stock used. Also, being enabled by our invention to construct the form of lighter gauge metal, we can produce a much sharper creasing edge on the form without as much grinding as has theretofore been necessary.

It has also been found that in forms heretofore constructed there is a tendency for the form to "whip", that is to say, to bend about a point near its base, due to the fact that the form is not sufficiently rigid. A reinforced form according to our invention is so constructed that the "whip" is taken out and the form will remain rigid in upright position while it is in use.

Other objects of our invention and additional advantages thereof will in part be obvious and in part more fully brought out as the description of the invention proceeds.

In the accompanying drawings we have illustrated a number of practical embodiments of our invention, but it is to be understood that the drawings are illustrative merely and that the invention is susceptible of a wide range of modification without departing from the salient features thereof or sacrificing any of its advantages.

In these drawings:

Fig. 1 is a view, in side elevation, of a hosiery drying form containing reinforcing members according to our invention;

Fig. 2 is a fragmentary perspective view showing the arrangement of the reinforcing members in the form illustrated in Fig. 1;

Fig. 3 is a view, in cross section, of the form illustrated in Fig. 1 showing particularly the arrangement of the reinforcing members; and

Figs. 4 to 8, inclusive, and 4a to 8a, inclusive, are views in cross section and perspective, respectively, of modifications of our invention, the figures bearing the subscript *a* being perspective views of the reinforcing members disclosed in the correspondingly numbered cross-sectional views.

Referring now to these drawings, the reference numeral 10 indicates, generally, a hosiery drying form of any well known construction and which comprises side members 11 and 12 suitably secured together, as by welding, at their edges 13 and 14. The form is preferably constructed of sheet metal, such as sheet steel, the side members 11 and 12 being cut to shape and then welded together by seam welding or other suitable process. However, it will be understood that the invention is not confined to a form of the particular description above set forth, but that on the other hand the invention may be employed in connection with forms of quite different construction.

In the present instance, we have shown the form 10 as provided with a series of reinforcing members 15 which are clearly shown in Figs. 2 and 3. These reinforcing members consist of a piece of sheet metal, such as steel, which is bent to form attaching portions 16 and a central web 17 connecting the attaching portions. Preferably, and as shown in Figs. 1 and 3, the reinforcing members are arranged in staggered relation on the interior of the form, the members being secured, as by spot welding, alternately to the sides 11 and 12. By so arranging the reinforcing members they overlap, and the loops formed by the webs 17 and the sides of the form constitute a channel, as clearly shown in Figs. 2 and 3, through which may be inserted a central rib or reinforcing bar 18 which then serves the purpose of locking to-

gether the reinforcing members and consequently, also, the sides 11 and 12.

It will be understood that after the sheets are cut to form the side members 11 and 12, the reinforcing members are secured thereto as, for example, by welding or other suitable means. Then the sides 11 and 12 are brought together and the central rib inserted as shown in Fig. 3 whereupon the edges 13 and 14 of the sides 11 and 12 are welded, or otherwise secured together.

Thus, it will be seen that the form described is reinforced by means of the members 15 against internal as well as external pressure. It will be clear, therefore, that the sides 11 and 12 are secured together not only at their edges 13 and 14 but, the arrangement of the reinforcing members and the location of the rib 18 serve to secure the sides together also along their longitudinal center. Thus, any tendency of the form to bulge due to the pressure of the heating medium within the form is effectually overcome and furthermore any tendency of the form to buckle during the process of its manufacture is also obviated. For example, in forms of the character above described, it is desirable to give the surface of the form a finish which shall be sufficiently rough to prevent creeping of stockings boarded on the form. Such a roughened surface may be produced, for example, by sandblasting under great pressure. During such process, the reinforcing members of our invention arranged as herein disclosed effectually prevent any denting or buckling of the form.

Furthermore, by the use of our invention, the sides 11 and 12 may be made of a lighter gauge metal than has heretofore been employed in hosiery drying forms with the result that sharper creasing edges 13 and 14 may be produced without the great amount of grinding heretofore necessary. The form, while of lighter metal is adequately supported and reinforced for a substantial part of its length and, as will be particularly noted from an inspection of Fig. 3, the resistance to torsional strain about the edges 13 and 14 is materially increased by reason of the location of the reinforcing members.

In Fig. 4 we have illustrated a modification of our invention. In this construction the form is provided with reinforcing members 19 and 20 secured, by any suitable means, to the sides 11 and 12, respectively, of the form. By reference to Fig. 4a it will be seen that the reinforcing member 19 is provided with an offset portion 21 which forms a recess for the reception of a tongue 22 which is cut from and bent out of the plane of the reinforcing member 20. In Fig. 4, the reinforcing members are shown in assembled relation and it will be clear that in this embodiment we have also provided reinforcing members which are secured to the sides of the form and which

have portions which are interlocked or interengaged. In this embodiment of our invention the form is also reinforced along its longitudinal center thus preventing separation of the side members 11 and 12 at their edges 13 and 14. The members 19 and 20 form a pair of reinforcing members and any desired number of such pairs may be provided and suitably spaced along the longitudinal center of the form. Inasmuch as the greatest tendency of the form to bulge or buckle is at its widest portion, that is to say, the portion from the base up to about the calf, it is unnecessary to provide the reinforcing members beyond the last-mentioned point.

15 A further modification of the invention is disclosed in Fig. 5 in which the form is shown to be provided with reinforcing members 23 and 24 suitably secured to the sides 11 and 12, respectively, of the form. The particular shape of these reinforcing members is more clearly illustrated in Fig. 5a and when assembled, as in Fig. 5, it will be seen that they have interengaging or interlocking portions 25 and 26, respectively.

25 In Fig. 6 a still further modification is illustrated and in this instance the form is seen to be provided with reinforcing members 27 and 28 secured, respectively, to the sides 11 and 12. Each of these reinforcing members is in the form of an angle and the portions 29 and 30 overlap and are secured together by any suitable means, such for example as a bolt 31.

35 In Fig. 7 we have illustrated still another modification of the invention. In this embodiment we have provided reinforcing members 32 and 33 which are in a form approximating the shape of a Z bar. The members 32 and 33 are shown in perspective in Fig. 7a and in assembled relation in Fig. 7. As is disclosed in the latter figure the reinforcing members have interengaging or interlocking portions 34 and 35, respectively.

45 In Fig. 8 we have illustrated still another modification of the invention. This modification is substantially like that disclosed in Fig. 7 except that the interengaging portions of the reinforcing elements 36 and 37 are substantially of U-shape, as clearly shown in the figure. It will also be noted that that portion of the reinforcing members which is secured to the sides 11 and 12 of the form is comparatively narrow so that the reinforcing members may be formed in the same die and may be secured to the sides of the form irrespective of variations in the contour of those sides.

55 It will be seen from the foregoing description that in all of the embodiments of our invention we have provided a hosiery drying form with reinforcing members secured to the sides of the form and extending inwardly therefrom. Furthermore, the reinforcing members are arranged in pairs and interen-

gage or are interlocked by suitable means for example, by the rib 18 in Fig. 2, the bolt 31 in Fig. 6, and in the other embodiments by reason of the shape of the reinforcing members. By our invention a hosiery drying form when made, for example, of sheet metal is adequately reinforced against pressures from within or without the form, thus rendering the structure rigid under all conditions of use. Clearly, also, by providing this central support for the sides of the form, we have overcome the tendency of the sides to separate at their joints and thus the form will remain leak proof for a much longer period than has heretofore been possible. While reinforcing members of this type are particularly useful in so-called "outsize" forms, their utility is by no means confined thereto, but in fact they may be used in all forms constructed of sheet metal and in every instance they will serve so to reinforce the form that the same may be made of lighter gauge metal than has heretofore been possible.

75 We claim:

1. A hollow garment drying form provided with reinforcing members extending inwardly from its opposing inner surfaces and located wholly within the form, said reinforcing members being connected together independently of the drying surface of the form.

80 2. A hollow garment drying form provided with reinforcing members extending inwardly from its opposing inner surfaces and located wholly within the form, said reinforcing members having portions which interlock with each other.

85 3. A hollow garment drying form provided with reinforcing members extending inwardly from its opposing inner surfaces and located wholly within the form, said reinforcing members having overlapping portions which are interconnected independently of the drying surface of the form.

90 4. A hollow garment drying form provided with pairs of reinforcing members extending inwardly from its opposing inner surfaces, said reinforcing members being located wholly within the form and the respective pairs being connected together independently of the drying surface of the form.

95 100 5. A hollow garment drying form provided with pairs of reinforcing members extending inwardly from its opposing inner surfaces and located wholly within the form, the reinforcing members extending from opposite surfaces having open portions in overlapping relation and a securing element extending through the openings in the overlapping portions to connect the members together.

105 110 115 6. A hollow garment drying form provided with reinforcing members extending inwardly from its opposing inner surfaces and located wholly within the form, said reinforcing members being channel-shaped and disposed in interengaging relation.

7. A hollow garment drying form provided with reinforcing members extending inwardly from its opposing inner surfaces and lying wholly within the form, said reinforcing members extending from one opposing surface to the other to prevent collapsing of the form and interlocking with each other to prevent bulging of the form.

In testimony whereof, we affix our signatures.
